ELECTRIC SIGN

Rudolf Wilde, Villa Park, Ill.

Application November 22, 1934, Serial No. 754,199

2 Claims. (Cl. 40—130)

This invention relates to improvements in electric signs.

One object of the invention is to provide a sign preferably of the neon type, comprising changeable sections provided with suitable contacts for establishing the circuit through the sign as the sections are assembled in the desired relation.

Neon signs are known which are formed in sections, each carrying a letter, but in forming a complete sign of the selected letters it is necessary to connect the terminals of the letters by means of conductors as the sections are placed in position.

Other types of neon signs are used each letter section of which is provided with an individual transformer. This construction, of course, is expensive where the signs frequently are to be altered, as a theater sign, for example, since it is necessary to have the complete alphabet of letters and of course several sections bearing the more frequently occurring letters.

By the present improvements, individual transformers for each letter are not required nor is it necessary to connect manually the terminals of each letter when a sign is altered. On the contrary, it is merely necessary to place the sections in position in the frame and improved contacts carried by the sections automatically establish the circuit through the entire sign. The alteration of a sign of the improved type is therefore a relatively simple matter.

A further object of the invention relates to improvements in the construction of contact members which establish the circuit through successive sections.

Other objects of the invention relate to various features of construction and arrangement of parts which will be apparent from a consideration of the following specification and accompanying drawing, wherein:

40 Figure 1 is a front elevation of a sign embodying the present improvements.

Figure 2 is an enlarged broken rear elevation of certain of the letter sections of the sign.

Figure 3 is a vertical section taken on line 3—3 of Figure 1.

Figure 4 is a section taken on line 4—4 of Figure 1.

Figure 5 is a side elevation of one of the contact posts.

Figure 6 is a detail of a contact member.

In the drawing, 10 is a frame which supports the individual sections or panels which carry the letters forming the sign. The frame 10 may be made of sheet metal and has the edge 11 of the upper

then downwardly to form a longitudinal channel 12. The upper edge 13 of the lower horizontal member of the frame is bent inwardly and then upwardly to form a flange 14.

The panels or sections indicated by the numeral 15 may be formed of sheet metal having inwardly directed stiffening flanges 16 on their vertical edges which terminate short of the upper and lower ends. In inserting a section in the frame the upper edge of the section is first inserted in the channel 12 and the inner end swung into engagement with the flange 14, the lower edge of the section having a complementary channel formed therein for receiving the flange 14, as shown in Figure 3.

To remove a section it is first raised slightly to clear the flange 14, and then lowered until the upper end clears the edge 11 of the upper frame member and then pulled outwardly.

The frame 10 shown in Figure 1 is shown provided with six sections 15. The end sections carry no letters. The sections which carry the letters have openings 17 formed therein for receiving terminals of the neon tubes of which the letters are formed. These terminals may be of any suitable construction. The letters are shown as being supported by conventional clips 18 in spaced relation with reference to the forward face of the sections 15.

The ends of the glass tubes of which the letters are formed are provided with any suitable terminals 18a which are passed through the openings 17 into contact with spring resisted terminals 19 carried by the insulating housings 20. The housings shown in the figures are of conventional construction and form no part per se of the present improvements.

Each of the sections 15 is provided with a pair of insulating posts 21 each disposed adjacent a margin of the sections. The posts 21 are secured to the sections 15 by means of bolts 22 or the like. The posts 21 are provided with rectangular openings 23 therein for receiving resilient contact members 24 which in the form shown are provided with spring-like convolutions 25. The inner end of each contact member preferably is provided with an opening for receiving a bolt 26 having a square shoulder 27 and which extends to the inner face of the post and is secured in position by a nut 28.

A short conductor 29 is secured at one end of the bolt 26 by a nut 30 and extends into contact with the spring resisted terminal of the terminal housing 20. The posts 21 as shown in Figures 1 and 2, are uniformly positioned on the backs

of the respective sections 15 whereby when the sections are in position in the frame 10, the posts will be in alignment. The posts are also positioned adjacent the vertical edges of the sections whereby the contact members 24 project slightly laterally of said vertical edges.

Thus in Figures 1 and 2 it will be seen that the resilient contacts 24 will be in abutting relation when the sections are assembled in the frame, whereby the current will flow in series through the individual letters of the sign.

By the construction described individual sections can readily be removed from the frame for rearrangement in spelling another word or words. 15 Where the particular word of a sign contains fewer letters than are required for filling the frame blank sections may be employed. The blank sections are constructed the same as the previously described sections, but have no letters 20 and are provided with a conductor 31 which extends from one of the contact posts 21 directly across to the other.

It is preferred to provide the rear portion of the frame with contact posts 32 which are similar to 25 contact posts 21 and are so disposed as to make electrical connections with the adjacent contacts carried by the end panels whether they be blank sections, as shown in Figure 1, or character sections. The contacts 32 are connected by conductors 33, 34 with the secondary of the transformer 35 which supplies current to the sign.

If desired, the posts 32 may be omitted and the ends of the conductors 33 and 34 connected to the appropriate contact members of the 35 respective sections, such as for example, the left hand contact of the section carrying the letter "S" of Figure 1, and the right hand contact of the section carrying the letter "N". However, the use of the posts 32 is preferred wherever feasible 40 since the alteration of a sign is facilitated in that there are then no separate conductors to be connected by the workmen.

As shown in Figure 6, each of the contact members 24 preferably is provided with a relatively 45 flat outer face, the edges of which are rounded. The spring convolutions 25 may be formed integral with the member 24 and preferably are formed of a flat strip of resilient conducting material. The general shape of the entire contact 50 is rectangular in cross section, and being positioned in a rectangular opening 23 cannot turn when the nut 23 is turned on or off, as will be seen.

In assembling the individual sections of the 55 sign shown in Figure 1, one of the end sections can first be inserted and the remaining sections successively placed in position. The rounded corners of the slightly projecting contacts 24 enable one of each abutting pair to slide over the other in placing a section in position and force each to recede slightly into the respective openings 23 and exert pressure one against the other to form a suitable electrical connection.

It will be understood that signs having a greater 60 number of letters can be constructed in accordance with the principle of the present improvements and that the removal of the sections

in rearranging the same to form a different word or words will require but a few minutes, and without the necessity of the workmen first detaching conductors extending from one terminal of a letter to another, and then re-establishing the 5 connections as the letters are placed in reassembled position.

Where the combined length of the glass tubes is such that two or more words can be served by the same transformer, the words can be spaced 10 by a blank section such as either of the end sections illustrated in Figure 1.

While I have shown and described an embodiment of my improvements for the purpose of illustration, I do not wish to be restricted specifically thereto except as so limited by the appended claims.

I claim:

1. An electric sign comprising a frame and a plurality of removable character sections adapted 20 to be inserted into final position in said frame and removed therefrom in a direction at right angles to the face of the frame, illuminatable characters on the forward faces of said sections, a pair of rearwardly extending insulating contact 25 posts uniformly disposed on the rear surface of each of said sections adjacent opposite margins thereof, said posts having recesses therein, and resilient contacts mounted in said recesses and electrically connected to the character on the 30 respective section, said contacts having ends projecting from said posts and beyond said section margins and having rounded edges whereby the same can be moved inwardly of said recesses by pressure exerted on said ends at right angles to 35 the direction of movement thereof by contacts of an adjacent section during insertion of the latter in the frame whereby any section can be inserted in final position in the frame or removed therefrom in a direction at right angles 40 to the face of the frame independently of the adjacent section or sections.

2. An electric sign comprising a frame and a plurality of removable character sections adapted 45 to be inserted into final position in said frame and removed therefrom in a direction at right angles to the face of the frame, illuminatable characters on the forward faces of said sections, a pair of rearwardly extending insulating contact posts 50 uniformly disposed on the rear surface of each of said sections adjacent opposite margins thereof, and resilient contacts carried by said posts and electrically connected to the character on the respective sections, said contacts each having a smooth portion projecting beyond the respective section margins and so shaped that the same 55 can be moved inwardly by pressure exerted on said portions at right angles to the direction of movement thereof by similar cooperating contacts of adjacent sections during insertion of the latter in the frame whereby any section can be inserted in final position in the frame or removed therefrom in a direction at right angles to the 60 face of the frame independently of the adjacent section or sections.

RUDOLF WILDE.
